UNITED STATES PATENT OFFICE.

ELIAS C. GLAZIER, OF ROCHESTER, NEW YORK.

REFLECTOR FOR LOCOMOTIVE HEAD-LIGHTS.

SPECIFICATION forming part of Letters Patent No. 414,807, dated November 12, 1889.

Application filed May 15, 1889. Serial No. 310,874. (No model.)

To all whom it may concern:

Be it known that I, ELIAS C. GLAZIER, a citizen of the United States, residing at Rochester, in the county of Monroe and State of New York, have invented new and useful Reflectors for Locomotive Head-Lights, of which the following is a specification.

This invention relates to reflectors for locomotive head-lights; and it consists in the improved construction and arrangement of parts, which will be hereinafter fully described, and particularly pointed out in the claims.

In the drawings, Figure 1 is a perspective view of a locomotive head-light having a reflector embodying my invention. Fig. 2 is a vertical transverse sectional view of the same. Fig. 3 is a perspective view showing the reflector detached from the lantern-casing. Fig. 4 is a longitudinal vertical sectional view of the same. Fig. 5 is a perspective view showing the parts of the reflector separate or detached from each other. Fig. 6 is a view showing the sections of the reflector connected adjustably by means of a hinge-joint.

The same letters refer to the same parts in all the figures.

Reflectors for head-lights have heretofore customarily been manufactured by beating them out of a single piece of metal, a process which, owing to their peculiar shape and size, has been troublesome and costly.

My improvements consist, primarily, in constructing the reflector in two sections, designated in the drawings by A A, and which, when placed together edge to edge, form a reflector-body of the usual parabolical shape. The sections A A are provided along their front or outer edges with flanges B, and the meeting edges of the said sections are likewise provided with flanges C, by means of which the said sections may be conveniently connected. The sections A A are of such a shape that they may conveniently be stamped from metal by means of a press and dies of suitable construction, and in this manner a very considerable saving may be effected in the manufacture of my improved reflectors.

When my improved reflector is to be used in a lantern-casing which is not provided with transparent sections, the sections A A, composing the said reflectors, may be connected

in any suitable manner, preferably by means of screws or bolts passing through the flanges C C and drawing the sections A A closely together. When it shall be desired, however, to use the reflector in a lantern-casing such as that illustrated in the drawings hereto annexed, the sides of which are provided with transparent signals D D, the sections A A must be connected in such a manner as to leave their meeting edges a suitable distance—say about three-eighths of an inch—apart, thus forming a slot of that width in the reflector, through which the same light which serves to illuminate the reflector will illuminate the said transparencies sufficiently for all practical purposes. The sections A A may be connected in any suitable manner which may be found most desirable and convenient. Thus the flange C of one of the sections may be provided with bolts E, extending through the other section, washers F of suitable thickness being interposed between the two sections for the purpose of making a slot or space of the desired width.

Another method of connecting the two sections is shown in Fig. 6 of the drawings, where the sections A A have been shown to be connected at their apices by means of a hinge-joint G, upon which the upper section may swing. The hinge-joint is so constructed as to leave the apices of the sections A A the desired distance apart, and lugs or studs H are placed upon the flange C of the lower section A, near the front end thereof, for the purpose of properly spacing the said sections. A cord I is attached to the upper section A and passed through the lantern-casing and over suitable guides or pulleys to the engineer's cab. It will be seen that when the reflector is thus arranged the light will normally shine through the slot or space between the sections A A, and thus serve to illuminate the transparent signals in the sides of the lantern-casing, while at the same time the light of the lantern is reflected or thrown in a forward direction in the usual manner. When it shall be desired, however, to cause the reflector to stop throwing the light in a forward direction, this may be effected by raising the upper section A upon its hinge to an approximately vertical position, when the forward reflection of the light will be destroyed without impairing the

illumination of the signals in the sides of the lantern-casing.

By constructing the reflector in the manner herein described it may be manufactured at a much reduced expense, and I have found by experimenting that the reflector may be constructed in this manner without impairing its power in the least, the horizontal opening or space between the two sections being quite invisible at a short distance. At the same time I have found that the light emitted through the said slot or opening is amply sufficient to illuminate the transparencies in the sides of the lantern-casing without the assistance of supplementary lights or sub-reflectors.

While I have herein described the preferred construction of my improved reflector, I would have it understood that I reserve the right to make any alterations in the details of the construction which practice may prove to be expedient.

Having thus described my invention, I claim—

1. A reflector for head-lights, constructed of sections divided on a horizontal longitudinal plane, substantially as set forth.

2. A parabolical reflector for head-lights, constructed of sections divided on a longitudinal plane and so connected as to leave a space or opening between the meeting edges of said sections, substantially as set forth.

3. A reflector for head-lights, constructed of separable sections having flanged meeting edges and connected to leave a space or opening between the said meeting edges, substantially as set forth.

4. A reflector for head-lights, the body of which is divided horizontally and longitudinally, the sections composing the said body being connected separably with their meeting edges a suitable distance apart, substantially as set forth.

5. A reflector for head-lights, constructed of longitudinally-divided separable sections con-

nected by a hinge-joint, substantially as set forth.

6. A reflector for head-lights, constructed of longitudinally-divided separable sections hinged together, in combination with lugs or studs arranged to hold the meeting edges of the said sections a suitable distance apart, substantially as set forth.

7. A parabolical reflector for head-lights, constructed of separable sections divided on a longitudinal horizontal plane and hinged together, in combination with a cord attached to the upper section and passing through the lantern-casing and over suitable guides to the engineer's cab, substantially as set forth.

8. The combination, with a lantern-casing the sides of which are provided with transparent signals, of a parabolical reflector constructed of separable sections divided on a longitudinal horizontal plane, connected to leave a space or opening between the meeting edges of the said sections, substantially as set forth.

9. The combination, with a lantern-casing provided with transparent signals, of a reflector constructed of separable sections hinged together and held normally apart to admit of the passage of light to illuminate such signals, substantially as set forth.

10. The combination, with a lantern-casing having transparent signals, of a reflector constructed of separable sections hinged together, and a cord attached to the upper hinged section and passing through the lantern-casing and over suitable guides to the engineer's cab, substantially as set forth.

In testimony that I claim the foregoing as my own I have hereto affixed my signature in presence of two witnesses.

ELIAS C. GLAZIER.
